ROBERT BOUTET, OF PARIS, FRANCE, ASSIGNOR TO LA SOCIETE FRANCAISE DES GLYCERINES, OF PARIS, FRANCE.

APPARATUS FOR DISTILLING GLYCERIN.

1,306,944.

Specification of Letters Patent.

Patented June 17, 1919.

Application filed May 22, 1918. Serial No. 236,024.

To all whom it may concern:

Be it known that I, ROBERT BOUTET, citizen of the Republic of France, and resident of Paris, France, (post-office address, 28 Rue de 5 Richelieu,) have invented a new and useful Apparatus for Distilling Glycerin, which improvements are fully set forth in the following specification.

This invention relates to an apparatus, by 10 means of which the distillation of glycerin can be carried out in specially favorable conditions.

An apparatus constructed in accordance with the invention is illustrated by way of 15 example in the accompanying drawing in which—

Figure 1 is a side elevation,

Fig. 2 is a plan, and

Fig. 3 shows, on an enlarged scale, details 20 of the atomizer.

The process involved in the invention consists in distilling glycerin by atomizing it by means of steam, nitrogen, air or any other desired gas, in a chamber heated to the desired temperature (about 180° C.), as distinguished from simply distilling glycerin in a still, which has the drawback that the liquid becomes more and more thick and more and more impure, the result being that 25 some of the glycerin is lost, the distilled glycerin is less pure, and the yield of the apparatus less high. The process according to the present invention obviates the said drawbacks.

30 The apparatus forming the subject of the present invention makes it possible to carry out the process of distillation by atomizing, mentioned above.

The apparatus is constituted by a sheet 40 metal cylinder A containing glycerin, in the interior of which is placed a concentric cylinder B in which the atomizing takes place.

In the vessel A, the glycerin is heated by a coil and raised to 180° C.; the vessel is supplied in a continuous manner by vacuum feed, and the level of the glycerin is maintained constant owing to the provision of a float cock C.

45 The vessel A communicates with a water condenser through a pipe D, so that any impurities volatilized below 180° C., can escape into the said condenser. The vacuum is regulated to a given value by a valve E arranged in the pipe D.

50 The vessel A also has a vacuum gage L, a drain cock F and a pipe G terminating in

a rose, which conveys glycerin to the atomizers H; the vessel B, or atomizing chamber, has a drain cock I connected to a drum collector for the residues which are produced as 60 the distillation proceeds, and which must be discharged without stopping the apparatus.

The vessel B communicates at the top, through a pipe S, with a series of condensers, and also carries a vacuum gage K. 65

The atomizers H, to the number of three, are mounted on the top of the vessel A at the apices of an imaginary equilateral triangle inscribed within an imaginary circle described from the center of said top with 70 a radius equal to two-thirds of that of the atomizing chamber. The atomizers are vertical, and their jets are directed downward.

Supply of glycerin to the atomizers is obtained and insured, on the one hand, by the 75 pipe G with the rose, and on the other hand by an injection of steam through a pipe M and by a regulation of the difference of vacuum between the vessels A and B, which regulation is effected to suit the difference 80 of level of the atomizers and of the glycerin, and in accordance with the output to be obtained.

In operation, and as previously stated, the glycerin in the vessel A is heated by the coil 85 therein to a temperature of approximately 180° C., the level of the glycerin being maintained constant by means of the float valve C. From said vessel A, the glycerin is supplied, by way of the pipe G, to the several 90 atomizers H which, in turn, extend into the central vessel or chamber B, wherein the atomizing takes place. Both vessels A and B are under vacuum, but to different degrees, this difference in degree being utilized to effect, in part, the passage of the glycerin from the outer or heating vessel A to the inner vessel B, and being regulated according to the difference of level between the atomizers and the surface of the glycerin. The pipe M, by 95 supplying steam to the atomizers, also serves to effect the feed of the glycerin thereto, and in addition acts in the usual way to effect the actual atomizing operation. As distillation proceeds, the impurities, if any, which are 100 volatilized below 180° C. in the vessel A, will escape therefrom through pipe D into the water condenser, while the residues collecting in the vessel B are discharged 105 through the drain cock I into the drum collector.

As both the latter and the several con-

densers may be of any desired type and, hence, form no part of the actual invention, it is considered unnecessary to illustrate them.

5 The apparatus makes it possible to distil glycerin of any kind, and to separate any mineral or organic impurities.

The vessels A and B, instead of being combined, may be independent of each other.

10 No claim is made herein to the method of operation, as such method forms the subject of my companion application, Serial No. 236,023, filed May 22, 1918.

I claim as my invention:

15 A distilling apparatus of the character specified, comprising, in combination, a vessel to contain the liquid to be distilled; a heating coil within said vessel; means for maintaining the liquid at a constant level in said

vessel; an atomizing vessel; a plurality of 20 atomizers mounted upon and projecting downwardly into the last-named vessel; a supply pipe to said atomizers from a point below the level of the liquid in the first-named vessel; means for maintaining both 25 vessels under different degrees of vacuum, to feed the liquid through said pipe to said atomizers; and means for injecting a gaseous fluid under pressure into and through said atomizers.

In testimony whereof I have signed this specification in the presence of two subscribing witnesses.

ROBERT BOUTET.

Witnesses:

GEORGE LOISEL,
JOHN F. SIMONS.
